[57] CLAIM

The ornamental design for a plant bracket with balls, as
shown and described.

DESCRIPTION

FIG. 1 is a side perspective view of a plant bracket
showing my new design;

FIG. 2 is a front elevational view of the plant bracket;

FIG. 3 is a rear elevational view of the plant bracket;

FIG. 4 is a left side elevational view of the plant bracket
(the left side being identical thereto);

FIG. 5 is a top plan view of the plant bracket;

FIG. 6 is a bottom plan view of the plant bracket; and,

FIG. 7 is a sectional view, illustrating the surface tex-
ture of the base plate enlarged in scale, taken along the
line 7—7 of FIG. 2.

FIG. 2
